Primary Examiner—Daniel Bui(74) *Attorney, Agent, or Firm*—Barley Snyder LLC(57) **CLAIM**

The ornamental design for a flat cable coupler, as shown and described.

DESCRIPTION

FIG. 1 is a front view of a flat cable coupler, with the lock plate in a closed position, showing our new design;

FIG. 2 is a top plan view thereof;

FIG. 3 is a bottom plan view thereof;

FIG. 4 is a rear plan view thereof;

FIG. 5 is a right-side view thereof;

FIG. 6 is a left-side view thereof;

FIG. 7 is a sectional view taken along the line A—A of FIG. 2;

FIG. 8 is a front view of the flat cable coupler of FIG. 1 showing the lock plate in an open position;

FIG. 9 is a top plan view thereof;

FIG. 10 is a bottom plan view thereof;

FIG. 11 is a rear plan view thereof;

FIG. 12 is a right side view thereof;

FIG. 13 is a left side view thereof;

FIG. 14 is a sectional view taken along the line B—B of FIG. 9;

FIG. 15 is a plan view of the flat cable coupler of FIG. 1 in use condition; and,

FIG. 16 is a sectional view taken along the C—C of FIG. 15. The broken line showing the environment is for illustrative purposes only and forms no part of the claimed design.
